UNITED STATES PATENT OFFICE.

FERDINAND SELLE, OF DETROIT, MICHIGAN.

TUBULAR BOW-SOCKET.

SPECIFICATION forming part of Letters Patent No. 242,562, dated June 7, 1881.

Application filed February 17, 1881. (No model.)

To all whom it may concern:

Be it known that I, FERDINAND SELLE, of Detroit, in the county of Wayne and State of Michigan, have invented an Improvement in 5 Tubular Bow-Sockets, of which the following is a specification.

The nature of my invention relates to certain new and useful improvements in carriage-bow sockets, by means of which a greater 10 strength is obtained than is had when constructed in the ordinary manner.

The invention consists in the peculiar construction of the parts, their combinations, and 15 operation, as more fully hereinafter described, and pointed out in the claims.

Figure 1 is an elevation, partially in section, of my improvement. Fig. 2 is a cross-section. Fig. 3 is a modification of the slat-iron.

In the accompanying drawings, A represents a tapering tube, the lower portion of 20 which is filled with wood, leaving a socket, B, at its upper end to receive the end of the wooden carriage-bow.

C is what is termed in the trade a "slat- 25 iron," provided with a pointed or gimlet screw, F, which is screwed into the lower end of the wood filling at the lower end of the tube. To strengthen the parts a nut, D, provided with flange a, is screwed upon the slat-iron until the 30 flange embraces the lower end of the tube, to which it is soldered, brazed, or otherwise similarly secured.

The back bow of a carriage-top is frequently 35 injured, when the top is thrown back, by impact with the stop which projects from the side of the carriage to sustain the weight of the top when in that position. To prevent

this I re-enforce that portion of the tube which forms a portion of the rear side of the bow with a circular plate, E, secured to the tube 40 by means of screws b, which pass into the wood filling, as shown, or in any other desired manner. This re-enforcing plate may extend the whole length of the tube or cover only 45 that portion which is brought into contact with the bearing-stop, as thought best, or as may be desired.

The parts A C D F and the wooden filling composing the socket are designed to be made and sold separate from the bow, and the 50 socket so formed makes a complete device, ready to be applied to the end of a bow at any time.

What I claim as my invention is—

1. The tubular socket B, having a wooden 55 filling, in combination with slat-iron C, provided with a shank, F, to be forced into said socket, and provided with a threaded portion for receiving a ring-nut, D, which is soldered to the socket after the shank is driven into 60 place, substantially as and for the purpose specified.

2. In combination with the socket B and the slat-iron C, having a screw-threaded shank, and a portion below the shank having a screw- 65 thread of a different pitch, the ring-nut B, provided with a flange, a, to be soldered to the socket A after the shank has been screwed therein, substantially as and for the purpose described.

FERDINAND SELLE.
